TAKE-UP DEVICE FOR KNITTING MACHINES

Fritz Lambach, Tenafly, N. J.

Application February 24, 1944, Serial No. 523,638

16 Claims. (Cl. 66—149)

1

My invention relates to knitting machines, and more particularly to a take-up device for taking up the fabric knitted by the knitting implements of a knitting machine.

An object of my invention is to provide a take-up device of such a construction, that, during the operation of the knitting machine, the tension roller forming a part of the take-up device exerts a uniform force on the fabric over the entire width thereof.

Another object of my invention is to provide a take-up device of above described type, which may be readily adjusted with great accuracy for a fabric of predetermined quality.

A further object of my invention is to improve upon the construction of take-up devices for knitting machines as now ordinarily made.

With the above and other objects of the invention in mind, the invention consists in the novel construction, arrangement and combination of various devices, elements and parts, as set forth in the claims hereof, an embodiment of the same being described in the specification and being illustrated in the accompanying drawings forming part of this specification, wherein

Fig. 1 is a fragmentary front elevational view of a take-up device according to the invention arranged in a warp knitting machine, some parts being broken away or being omitted for a better illustration of the elements forming a part of the invention,

Fig. 2 is a fragmentary top plan view of a detail of the take-up device shown in Fig. 1, and

Fig. 3 is a sectional view of the take-up device taken on line 3—3 of Fig. 1.

Referring to the drawings, 10 generally indicates the frame of a warp knitting machine. As best shown in Fig. 3, the fabric 12 knitted by the knitting implements 14 of the warp knitting machine is taken up by a take-up roller 16 journaled in suitable bearings of the frame 10 and intermittently driven by a suitable drive to be described hereinafter. The fabric 12 passing over a guiding rod 18 arranged in the frame 10 of the warp knitting machine is subject to a certain tension caused by a movable tension roller 20.

The arrangement of the tension roller 20 is as follows: The tension roller 20 is rotatably mounted in a pair of spaced supporting members or arms 22, 24. Each of said supporting members 22, 24 is swingably mounted on the frame 10 of the warp knitting machine. The supporting member 22 is swingable about the shaft 26 carrying some elements of the drive for the take-up

2

roller 16 as will be described hereinafter, and the supporting member 24 is swingable about a shaft 28 coaxially arranged in the frame of the warp knitting machine with said first mentioned shaft 26. One end of a connecting link 30 is pivoted to an extension 32 of the supporting arm 22 at 34 and likewise one end of a connecting link 36 is pivoted to an extension 38 of the supporting arm 24. The other lower end of the connecting link 30 is pivoted at 40 to one arm 42 of a bell-crank lever 44 keyed to a shaft 46 journalled in the frame 10 of the warp knitting machine. Likewise, the lower end of the connecting link 36 is pivoted to an arm 48 of a bell-crank lever 50 keyed to the same transverse shaft 46. Apparently the pivotally connected connecting link 30 and arm 42 and the pivotally connected connecting link 36 and arm 48 form spaced parallel link-mechanisms coupled with each other through the shaft 46, one end of each link-mechanism being pivoted to one of the supporting members 22, 24, the other end of each link-mechanism being swingably mounted on the knitting machine at 46. Each arm 42, 48 of the pair of bell-crank levers 44, 50 carries a weight 52, 54 slidably and adjustably arranged on said arm. The weight may be held in its adjusted position by means of an adjusting screw or the like. The weights 52 and 54 tend to urge the tension roller 20 against the fabric 12. Obviously, the larger the distance between the weight and the axis of the shaft 46, the larger the tension in the fabric caused by the tension roller 20. Each of the weights may be readily adjusted in a predetermined position for a predetermined degree of the tension in the fabric by means of a scale 56 arranged on the arm of the bell-crank lever carrying the weight. Thus, the weights 52 and 54 may be used for a rough adjustment of the tension in the fabric.

40. The following additional adjusting means are arranged for a fine adjustment of the tension in the fabric. A tension spring 58 is stretched between the arm 60 and one end of an adjusting rod 62. The other end of said adjusting rod 45 62 is flattened and passes freely through a hole 66 in a bracket 68 secured to the frame 10 of the warp knitting machine. Furthermore, said flattened end 64 is provided with threads for engagement with the threaded bore of a crank 70 abutting against the surface of the bracket 68. As will be readily understood, a rotation of the crank 70 causes a displacement of the adjusting rod 62 in the direction of its longitudinal axis and, consequently, a change in the force of 50 the tension spring 58 acting on the arm 60 of

the bell-crank lever 44. The tension spring 58 counteracts to a certain degree the load on the tension roller 20 caused by the action of the weight 52. A scale 72 arranged on the flattened end 64 of the adjusting rod 62 may be used for an adjustment of a predetermined degree of the force exerted by the tension spring 58 on the tension roller 20. In a similar manner a tension spring (not shown in Fig. 1) is arranged between the arm 74 of the bell-crank lever 50 and an adjusting rod 76, the threaded end 78 of which is engaged with the threaded bore of a crank 80.

Each connecting link 30, 36 carries an adjustable stop 82, 84. Said stops 82 and 84 cooperate with a member 86 of the frame of the warp knitting machine for limiting the lowermost position of the tension roller 20.

As will be apparent from above, the mechanism 30, 36, 42, 48 and 46 serves as a coupling between the spaced supporting members 22 and 24 of the tension roller 20, so that said two supporting members 22 and 24 are moved at the same time and displaced to the same degree. Consequently, the movements of the tension roller 20 during the operation of the warp knitting machine are positively controlled by the mechanism 22, 24, 30, 36, 42, 48, 46 including a parallel guide engaged with spaced points of the tension roller, so that said tension roller is held in positions substantially parallel to each other during its displacements and a uniform displacement of the tension roller 20 over the entire width of the fabric 12 is obtained.

The drive of the take-up roller 16 is as follows: A sprocket gear 88 keyed to a shaft 90 journaled in the frame 10 of the warp knitting machine may be rotated by the main shaft (not shown) of the warp knitting machine through the medium of a chain 92. One arm 94 of a U-shaped crank 96 is keyed to the shaft 90, the other arm 98 of said crank 96 has a slot 100 for engagement with the flattened portion 102 of a bolt 104 inserted into a bore of a feed rod 106. A shoulder 108 of the bolt 104 carrying a pointing mark 110 abuts against the arm 98 carrying a scale 112. The bolt 104 is held in engagement with the feed rod 106 by means of a split-pin 114 or the like. The flat portion 102 of the bolt 104 may be displaced in the slot 100 of the arm 98 for an adjustment of the eccentricity caused by the distance between the axis of the shaft 90 and the axis of the bolt 104. The flattened portion 102, and consequently the bolt 104, may be held in its adjusted position relative to the slot 100 by means of a nut 116 screwed on the threaded end 118 of the bolt 104. The eccentricity of the axis of the bolt 104 relative to the axis of the shaft 90 determines the feed of the take-up roller 16 in a manner to be described hereinafter. Therefore, a predetermined degree of the feed of the take-up roller 16 may be readily adjusted by means of the pointing mark 110 cooperating with the scale 112.

As pointed out above, one end of the feed rod 106 carries the bolt 104. The other end of the feed rod 106 has a slot 120 for engagement with a pin 122 carried by an arm 124 of a member generally indicated by 126. Said member 126 is swingably mounted on the shaft 26 carrying the supporting member 22 of the tension roller 20. The member 126 has a second arm 128 and a third arm or feeler arm 130 for a purpose to be described hereinafter. A tension spring 132 stretched between a pin 134 secured to the feed

rod 106 and a hook 136 secured to the arm 124 of the member 126 tends to urge the pin 122 carried by the arm 124 towards the lower end of the slot 120. The lower-most position of the pin 122 in the slot 120, however, is determined by the feeler arm 130 of the member 126. Said feeler arm 130 may come to rest on an extension 138 of the tension roller. If the tension roller 20 and feeler arm 130 are in the position shown in Fig. 3, there is a slight distance between the lower end of the slot 120 and the pin 122. During the operation of the warp knitting machine, the feed rod 106 is moved back and forth in the direction of the arrows A and B owing to the eccentricity adjusted by the setting means 100, 102, 104, 118 described above. As soon as, during the movement of the feed rod 106 in the direction of the arrow A, the lower end of the slot 120 abuts against the pin 122 carried by the arm 124, the arm 124 is swung in clockwise direction, as viewed in Fig. 3, whereby a spring loaded pawl 140 carried by the arm 128 of the member 126 causes a slight rotation of a ratchet wheel 142 engaged with the pawl 140 and rotatably mounted on the shaft 26 carrying the supporting member 22 of the tension roller 20. The slight rotation of the ratchet wheel 142 is transmitted to the take-up roller 16 for the taking up of the fabric through the medium of a gear 144 connected with said ratchet wheel 142 and engaged with a gear 146, which in turn is in mesh with a gear 148 meshing with a gear 150 connected with the take-up roller 16. A spring loaded arresting pawl 152 mounted on a pin 154 secured to a member 156 carried by the guiding rod 18 serves to hold the ratchet wheel 142 and, consequently, the take-up roller 16 in its advanced position after the performance of a feeding stroke of the feed rod 106. During the return of the feed rod 106 in the direction of the arrow B, the spring 132 draws the arm 124 of the member 126 in counterclockwise direction until the feeder arm 130 of said member 126 abuts against the extension 138 of the tension roller 20.

As will be readily understood from above, if, during the operation of the warp knitting machine, a change in the tension of the fabric 12 occurs with the result of a change in the position of the tension roller 20, a change in the distance between the pin 122 and the lower end of the slot 120 occurs at the same time, so that the take-up roller 16 is automatically fed to a greater or smaller extent, until the normal tension in the fabric 12 is readjusted and the tension roller 20 returns into its original position.

It may be mentioned that the sprocket gear 88 is rigidly connected with a gear 158 mounted on the shaft 90 described above. Said gear 158 is in mesh with a pinion 160 on the stationary coupling member 162 of a friction clutch 164. The slidable coupling member 166 of said clutch is engaged with the hand wheel shaft 168 carrying a number of hand wheels 170. The shifting member for the slidable coupling 166 is omitted in Fig. 1, and the coupling members 162 and 166 are shown as being disengaged from each other. If the coupling members 162 and 166 are engaged with each other, the rotatable elements of the warp knitting machine may be rotated by hand by means of a hand wheel 170.

The operation of the take-up device is as follows: Preferably, a table is given to the operator of the machine indicating certain values on the scales 56, 72, 112 to be adjusted for a fabric of a

certain quality; for example, the weights 52 and 54 are adjusted to the value 3 on the scale 56 and the tension spring 58 is adjusted to the value 5.2 on the scale 72, so that a predetermined load acts on the tension roller 20 for subjecting the fabric 12 to a certain tension. Furthermore, for example, the setting means 100, 102, 104, 118 are set for the value 2 on the scale 112 for a certain degree of the feeding of the take-up roller 16. As will be readily understood, the provision of the scales permits a ready adjustment of the warp knitting machine to any fabric to be knitted.

If, during the knitting operation, a change in the tension in the fabric 12 occurs, which might result in a lifting or lowering of the tension roller 20, such a lifting or lowering of the tension roller takes place at a uniform degree over the entire length of the tension roller owing to the positive control of the movements of the latter by the mechanism 22, 24, 30, 36, 42, 48, 46, so that a uniform tension over the entire width of the fabric 12 is maintained.

I have described a preferred embodiment of my invention, but it is clear that numerous changes and omissions may be made without departing from the spirit of my invention.

What I claim is:

1. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a shaft journalled in said knitting machine, a pair of spaced levers keyed to said shaft, and a pair of connecting links, each connecting link connecting a supporting member with a lever, and said pair of spaced supporting members carrying said tension roller for controlling the movements thereof.

2. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a shaft journalled in said knitting machine, a pair of spaced levers keyed to said shaft, a pair of connecting links, each connecting link connecting a supporting member with a lever, said pair of spaced supporting members carrying said tension roller for controlling the movements thereof, and an adjustable load acting on said supporting members for an adjustment of the tension in the fabric by means of the tension roller carried by said supporting members.

3. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension

said fabric, a pair of spaced supporting members swingably mounted on said knitting machine, a shaft journalled in said knitting machine, a pair of spaced levers keyed to said shaft, a pair of connecting links, each connecting link connecting a supporting member with a lever, said pair of spaced supporting members carrying said tension roller for controlling the movements thereof, a first adjustable load acting on said supporting members for a rough adjustment of the tension in the fabric by means of the tension roller carried by said supporting members, and a second adjustable load acting on said supporting members and counteracting said first adjustable load for a fine adjustment of the tension in the fabric.

4. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a shaft journalled in said knitting machine, a pair of spaced levers keyed to said shaft, a pair of connecting links, each connecting link connecting a supporting member with a lever, said pair of spaced supporting members carrying said tension roller for controlling the movements thereof, and a weight adjustably mounted on at least one of said levers for an adjustment of the tension in the fabric by means of the tension roller carried by said supporting members.

5. In a take-up device as claimed in claim 4, said lever being equipped with a scale for adjusting the weight in a predetermined position.

6. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a shaft journalled in said knitting machine, a pair of spaced levers keyed to said shaft, a pair of connecting links, each connecting link connecting a supporting member with a lever, said pair of spaced supporting members carrying said tension roller for controlling the movements thereof, a weight adjustably mounted on at least one of said levers for a rough adjustment of the tension in the fabric by means of the tension roller carried by said supporting members, at least one arm secured to said shaft, and an adjustable load acting on said arm and counteracting said weight for a fine adjustment of the tension in the fabric.

7. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting

machine, a shaft journalled in said knitting machine, a pair of spaced levers keyed to said shaft, a pair of connecting links, each connecting link connecting a supporting member with a lever, said pair of spaced supporting members carrying said tension roller for controlling the movements thereof, a weight adjustably mounted on at least one of said levers for a rough adjustment of the tension in the fabric by means of the tension roller carried by said supporting members, at least one arm secured to said shaft, a spring connected with said arm and arranged for counteracting said weight, and adjusting means associated with said spring for adjusting the force thereof for a fine adjustment of the tension in the fabric.

8. In a take-up device as claimed in claim 7, said adjusting means including a scale for adjusting a predetermined force of the spring.

9. In a take-up device as claimed in claim 7, said lever being equipped with a scale for adjusting the weight in a predetermined position, and said adjusting means including a scale for adjusting a predetermined force of the spring.

10. A take-up device for taking up the fabric knitted by the knitting implements of a knitting machine, comprising: a take-up roller rotatably mounted in the knitting machine, an adjustable eccentric feed motion associated with said take-up roller for feeding same for the taking up of the fabric, a tension roller for engagement with the fabric extending between the knitting implements and the take-up roller so as to tension said fabric, a mechanism movably arranged in said knitting machine, said mechanism being engaged with said tension roller for controlling the movements thereof, an adjustable load acting on said tension roller for an adjustment of the tension in the fabric, setting means including a scale associated with said adjustable eccentric feed motion for adjusting a predetermined degree of eccentricity, and adjusting means including a scale associated with said adjustable load for adjusting a predetermined action of the load.

11. A take-up device for taking up the fabric knitted by the knitting implements of a knitting machine, comprising: a take-up roller rotatably mounted in the knitting machine, an adjustable eccentric feed motion associated with said take-up roller for feeding same for the taking up of the fabric, a tension roller for engagement with the fabric extending between the knitting implements and the take-up roller so as to tension said fabric, a mechanism movably arranged in said knitting machine, said mechanism being engaged with said tension roller for controlling the movements thereof, a first adjustable load acting on said tension roller for a rough adjustment of the tension in the fabric, a second adjustable load acting on said tension roller and counteracting said first adjustable load for a fine adjustment of the tension in the fabric, setting means including a scale associated with said adjustable eccentric feed motion for adjusting a predetermined degree of eccentricity, first adjusting means including a scale associated with said first adjustable load for adjusting a predetermined action of the latter, and second adjusting means including a scale associated with said second adjustable load for adjusting a predetermined action of the latter.

12. A take-up device for taking up the fabric knitted by the knitting implements of a knitting machine, comprising: a take-up roller rotatably

5 mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a pair of spaced link-mechanisms, each link-mechanism including a plurality of links pivotally connected with each other, one end of each link-mechanism being pivotally connected with one of said supporting members, the other end of each link-mechanism being swingably mounted on the machine, said spaced link-mechanisms being coupled with each other for a simultaneous movement thereof and of said spaced supporting members, and said pair of spaced supporting members carrying said tension roller for controlling the movements of the latter.

13. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a pair of spaced link-mechanisms, each link-mechanism including a plurality of links pivotally connected with each other, one end of each link-mechanism being pivotally connected with one of said supporting members, the other end of each link-mechanism being swingably mounted on the machine, said spaced link-mechanisms being coupled with each other for a simultaneous movement thereof and of said spaced supporting members, said pair of spaced supporting members carrying said tension roller for controlling the movements of the latter, and an adjustable load acting on said supporting members for an adjustment of the tension in the fabric by means of the tension roller carried by said supporting members.

14. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a pair of spaced link-mechanisms, each link-mechanism including a plurality of links pivotally connected with each other, one end of each link-mechanism being pivotally connected with one of said supporting members, the other end of each link-mechanism being swingably mounted on the machine, said spaced link-mechanisms being coupled with each other for a simultaneous movement thereof and of said spaced supporting members, said pair of spaced supporting members carrying said tension roller for controlling the movements of the latter, a first adjustable load acting on said supporting members for a rough adjustment of the tension in the fabric by means of the tension roller carried by said supporting members, and a second adjustable load acting on said supporting members and counteracting said first

adjustable load for a fine adjustment of the tension in the fabric.

15. A take-up device for taking up the fabric knitted by the knitting implements of a knitting machine, comprising: a take-up roller rotatably mounted in the knitting machine, a drive associated with said take-up roller, said drive being capable of rotating said take-up roller for taking up the fabric, a tension roller for engagement with the fabric extending between the knitting implements and the take-up roller so as to tension said fabric, a pair of spaced supporting members swingably mounted on said knitting machine, a pair of spaced link-mechanisms, each link-mechanism including a plurality of links pivotally connected with each other, one end of each link-mechanism being pivotally connected with one of said supporting members, the other end of each link-mechanism being swingably mounted on the machine, said spaced link-mechanisms being coupled with each other for a simultaneous movement thereof and of said spaced supporting members, said pair of spaced supporting members carrying said tension roller for controlling the movements of the latter, and a stop arranged on the knitting machine for limiting the lowermost position of the tension roller.

16. A take-up device for taking up the fabric knitted by the knitting implements of a knitting machine, comprising: a take-up roller rotatably

mounted in the knitting machine, a drive associated with said take-up roller, said drive including a ratchet gearing comprising a ratchet wheel for an intermittent feed of the take-up roller for taking up the fabric, a shaft carrying said ratchet wheel, a tension roller for engagement with the fabric extending between the knitting implements and the take-up roller so as to tension said fabric, a pair of spaced supporting members swingably mounted on said knitting machine, one of said supporting members being swingably mounted on said shaft carrying the ratchet wheel, and coupling means connecting said spaced supporting members with each other for a simultaneous movement thereof, and said pair of spaced supporting members carrying said tension roller for controlling the movements thereof.
